SOCKET DEVICE FOR VACUUM TUBES

Filed May 7, 1926

By his Attorneys

Philip S. Sawyer, Rice & Kennedy

UNITED STATES PATENT OFFICE.

FREDERICK REUTTER, OF WATERBURY, CONNECTICUT, ASSIGNOR TO SCOVILL MANUFACTURING COMPANY, OF WATERBURY, CONNECTICUT, A CORPORATION OF CONNECTICUT.

SOCKET DEVICE FOR VACUUM TUBES.

Application filed May 7, 1926. Serial No. 107,318.

This invention relates to improvements in socket devices for vacuum tubes such as are generally employed in radio apparatus.

It is known that such vacuum tubes are relatively sensitive to shock and that any jarring or vibration of such a tube while in operation is disadvantageous for reasons well understood by those skilled in the art.

It has been common heretofore to provide a spring mounted socket for such a tube in order to prevent or, at least, minimize the transmission of shocks or vibrations to the tube.

By the present invention there is provided a spring mounting which will have a sufficient length of spring to give the desired resiliency, within a limited space, while at the same time providing contact terminals for the requisite electric circuits in an efficient manner. The invention consists in the features, details of construction and combination of parts which will first be described in connection with the accompanying drawings and then particularly pointed out.

In the drawings,—

Figure 1 is a side elevation, partly in section, of a socket-device embodying the invention, with a vacuum tube in place;

Figure 2 is a bottom plan view of the socket-device; and

Figure 3 is a section on line 3—3 of Figure 2 of the spring device secured to the base-board.

Referring to the drawings, 1 is a base-board of non-conductive material, such for example as fibre, and, in the particular embodiment shown, is suitable for use in a radio receiver set.

This base-board is provided with a central circular opening whose diameter is greater than that of the socket base 2. The latter is usually circular and is made of insulating material such, for example, as hard rubber or a suitable phenolic condensation product, such for example, as the material known on the market as bakelite.

To the socket base 2 is secured a socket 3 made of metal. This socket is advantageously formed of drawn tubing so as to be sufficiently strong and rigid while at the same time being of relatively light weight. This socket has its bottom end flanged outward, as shown at 4, the flange being provided with a plurality of lugs 5. In the

embodiment illustrated, four such lugs are shown, these being equally spaced apart. Each lug 5 is perforated and is secured to the socket base 2 by tubular eyelet rivets.

The socket and socket base are supported on a plurality of leaf or plate spring devices, four of such devices being shown in the drawings. Each spring device may be considered as comprising three parts, viz, a main portion indicated at 6, an inwardly extending spring contact portion 7, which is an extension of the main portion, and an outward extending spring tongue 8. The latter is formed by stamping it up from the main portion 6, thereby leaving two relatively narrow strips of the main portion at each side of the spring tongue. The latter connects only at its inner end with the outer end of the main portion 6, and is bent first sharply upward from the main portion and then at a lesser angle to the main portion.

The outer end of each spring tongue 8 is perforated and is secured to the socket base 2 by eyelet rivets, the points of connection of the spring tongues to the socket base being intermediate the points of connection of the lugs 5 to the socket base.

The outer end of the main portion 6 of each spring device is perforated whereby it may be secured to the under side of the base-board 1 in any suitable way, as for example, by eyelet rivets, as shown in the drawings. Also, the said main portion has a stud or button indicated at 6^a, which may be pressed or struck up from the metal of said main body portion. This part 6^a may enter a recess or hole in the base-board 1 to prevent lateral movement of the spring device. The outer end of the main portion 6 may be bent down at an angle and may also have ears 6^b, between which a connecting wire may be inserted and held by bending the ears down and soldering.

The spring contact portions 7 are bent upward above the plane of the main portions 6, as will be seen from the drawings.

In the best embodiment of the invention, the spring devices extend radially with respect to the socket and are all of the same size, so that they press up uniformly on the terminals of the vacuum tube and react uniformly on the socket-base.

The radio tube consists of the usual exhausted receiver 9 of glass, containing a

filament 10 having terminals 11 and 12, and also containing a plate 13 and a grid 14, the terminals of which are indicated at 15 and 16 respectively. The tube has the usual base 17 having a radially projecting pin 18. The socket 3 is provided with a bayonet slot to receive this pin 18, this slot being indicated at 19.

The location of the terminals 11 and 12 for the filament and the terminals 15 and 16 for the plate and grid respectively is such that when the tube is inserted in the socket the respective terminals will engage the corresponding spring contact portions 7 and when the tube is rotated to lock it in the socket, the terminals 11, 12, 15 and 16 will slide along the face of their corresponding spring contact portions 7, thus making a rubbing contact and insuring a good electrical connection between the terminals and the contact portions. The amount of rotation of the tube permitted by the travel of the pin 18 in the horizontal or locking portion of the bayonet slot 19 is not great enough to allow the terminals 11, 12, 15 and 16 to pass off the corresponding contact portions 7.

The base-board 1 may be provided with a plurality of binding posts 20, 21, 22, 23 which are connected with the outer ends of the respective main portions 6, so that the circuit connections may be made to the filament and to the plate and grid respectively.

It will be seen that the terminals of the radio tube are in contact with spring contact devices having a spring action due to the combined length of the main portion 6 and of the spring contact portion 7, while the spring support for the socket base 2 has a length substantially equivalent to the combined length of the main portion 6 and the spring tongue 8, and since the tongue 8 is relatively narrow and the main portion 45 is cut away by the stamping up of the spring tongue, the spring support of the socket base and of the tube is very much more resilient than it would be if the socket base was secured directly to the main portions 7.

What I claim is:

1. A socket device for vacuum tubes, comprising a socket-base of insulating material, a socket secured to said socket-base and arranged to hold the vacuum tube, and a plurality of spring devices, each extending inwardly to form a spring contact for the terminal of the vacuum tube and having a spring portion integral with, but partly severed from, the device, said portion having a free end secured to the socket base. 60

2. A socket device for three-electrode vacuum tubes, comprising a socket-base of insulating material, a socket secured to said socket-base and arranged to hold the vacuum tube, and four spring devices, each comprising a main portion, a spring tongue and a spring contact portion, the spring tongue having its inner end joined to the said main portion and its outer end secured to the 70 socket-base, the spring contact portion extending inward and being arranged to make an electrical contact with the respective terminal of the vacuum tube, said four spring-devices extending radially with respect to 75 the socket and being spaced apart equally.

3. A socket device for vacuum tubes comprising a socket-base of insulating material, a socket secured to said socket-base and arranged to hold a vacuum tube and a plurality of spring devices each extending inwardly to form a spring contact for a terminal of the vacuum tube and having a spring portion integral with but partly severed from the device, said portion having 80 a free end secured to the socket-base, and outwardly extending lugs on said device for receiving a conductor. 85

4. A socket device for vacuum tubes comprising a socket-base of insulating material, 90 a socket secured to said socket-base and arranged to hold the vacuum tube, and a plurality of spring devices each extending inwardly to form a spring contact for a terminal of the vacuum tube, and having a 95 spring portion integral with but partly severed from the device, said portion having a free end secured to the socket-base.

In testimony whereof, I have hereunto set my hand.

FREDERICK REUTTER.
